UNITED STATES PATENT OFFICE.

EMERY M. HAMILTON, OF NEW YORK, N. Y.

TYPE-WRITING MACHINE.

SPECIFICATION forming part of Letters Patent No. 430,772, dated June 24, 1890.

Application filed February 10, 1890. Serial No. 339,767. (No model.)

To all whom it may concern:

Be it known that I, EMERY M. HAMILTON, of the city, county, and State of New York, a citizen of United States, have invented certain new and useful Improvements in Type-Writing Machines, of which the following is a full, clear, and exact description, reference being had to the accompanying drawings, forming part of this specification.

- 10 My invention relates to the paper-carriage and platen of a type-writing machine; and my invention consists in the hereinafter-described devices whereby the paper to be printed upon is held in position on the platen, whereby the carriage is mounted and adapted to effect its longitudinal movement across the machine in the operation of printing, and whereby the platen is rotated to produce the line-spacing.
- 15 Figure 1 is a plan of a paper-carriage containing my invention and showing its connected and actuating devices in a type-writing machine. Fig. 2 is a front elevation of the carriage. Fig. 3 is an end elevation of the carriage, showing the ways upon which it moves in cross-section. Fig. 4 is a vertical cross-section of the carriage on line xx . Fig. 1. Fig. 5 is a side elevation in normal position of the devices for rotating the platen.
- 20 Fig. 6 is a similar view of the same in position at the conclusion of a partial rotation of the platen. Figs. 7 and 8 are respectively an end elevation and a plan of the ways on which the carriage travels.
- 25 The paper-carriage in its general structure is similar to the usual carriages in type-writing machines—that is to say, the carriage-frame is composed of a rod a , extending longitudinally of the rearward side of the carriage and fixed on a bar a' , which is adapted to slide in ways across the machine. A corresponding rod a^2 constitutes the front of the frame, and has a friction-roller a^3 , which travels on a rail a^4 . End yokes a^5 and a^6 are pivotally mounted at one end on the rod a , and are united at their opposite ends by the rod a^7 . The cylindrical platen B is journaled in said yokes, as shown. The rail a^4 bears the usual letter-scale shown, with which is combined the customary pointer a^8 on the front of the carriage. A paper-guide a^9 may be provided on the carriage-frame in front of

the platen. The carriage is thus adapted to swing on the rod a , so as to expose the printing-line on the platen to the operator in the usual manner. The carriage may be given its longitudinal movement across the machine by the usual pulling-cord a^9 , attached at one end to the bar a' of the carriage and at the opposite end to the well-known spring-drum a^{10} . The motion of the carriage may be controlled in its said longitudinal movement to effect the spacing on the printing-line between letters and words by the customary rack a^{11} , fixed and extending longitudinally on the carriage-frame, into which the dogs C and C' take, and which dogs are controlled usually by springs, and are actuated by the universal lever C^2 of the machine through the arm c thereof and a reciprocatory bar C^3 . It will be understood that the vibration of the universal lever C^2 , by engagement with its arm c' of either a finger-key lever, as shown at C^4 , or the spacing-key lever, as shown at C^5 , will swing the arm c of said universal lever so as to reciprocate the bar C^3 and cause the dog C as it engages a tooth on the rack a^{11} , and thus holds the carriage at rest, to at the same time rock the dog C' on its pivot by engagement with the heel c^6 thereon, so as to disengage the dog C' from the rack. Upon the release of the universal lever by the key-lever the arm c of said universal lever will be reversely vibrated, and as the retracting-spring c^7 of the dog C withdraws said dog from its engagement with the rack the dog C' will be consequently released, and will be actuated by its spring c^8 to move on its slotted pivot-bearing, so as to engage a succeeding tooth on the rack a^{11} . The dog C' may be provided with an arm c^9 , and a sliding bar c^8 may be arranged, as shown, to engage said arm c^9 , whereby the dog C' may be oscillated to disengage it from the rack a^{11} , whereupon the carriage may be moved freely back and forth on its ways.

In the construction shown and described I find it desirable to construct the bar C^3 in two parts, which are jointed together endwise at c^7 by a screw-joint, and to connect one end of said bar to the arm c of the universal lever by journaling the former in the latter, as shown at c^8 . By this means the length of the bar C^3 may be varied and adjusted to its con-

nected devices to take up any wear thereof or lost motion, and so as to give the requisite movement to the dogs C and C' from the oscillations of the universal lever.

- 5 The way D may be composed of two parallel plates d d' , adapted to be mounted on the machine-frame adjustable relatively to each other—as, for example, by means of slotted apertures b^2 in one or both of said plates and 10 screws p^3 passing through said apertures and into the machine-frame. In the upper faces of these parallel plates I form a longitudinal dovetail groove b^4 , making a portion of the groove in each plate, as shown, and adapted 15 to receive a corresponding longitudinal dovetail rib a^{12} , formed on the bar a' , as shown. The positions of the groove and rib may of course be reversed, in which case a portion of the dovetail rib would be formed on each of 20 the plates d d' .

A further feature of my invention consists in the combination, with the cylindrical platen B, of a pressure-plate E, in the following manner: This plate E extends longitudinally of the platen continuously from end to end, and is formed with a plane portion e , which is tangential to the circumference of the platen, thus constituting a throat-like space between the plate and the platen, into 25 which the paper to be placed on the platen may be introduced. The portion of the plate E which extends over the platen toward the printing-line thereon is curved flatwise, as at e' , to conform to the platen's periphery, as 30 shown. The plate E is pivotally hung upon the rod a of the carriage-frame, so as to swing thereon and traverse the same with the platen, and this is accomplished by means of lugs e^2 , formed on the plate E at the ends 35 thereof by bending the plate angularly, as shown, which lugs are perforated to fit to the rod a . Upon each end of the plate E are fixed spring-arms e^3 , preferably in the form of leaf-springs, as shown, which are adapted 40 to reach under the platen to and be seated upon the front rod a^2 of the carriage-frame. The action of these spring-arms e^3 is therefore to hold the curved face e' of the plate E to the platen-surface with a yielding pressure, so that while the papersheet to be printed 45 upon will be held firmly to the platen without the aid of a pressure-roller the platen may be freely rotated to introduce the paper to position thereon and to feed the paper line by line in printing. The spring-arms e^3 being located at the extreme ends of the plate E, and the plate being made of a requisite length, said arms may be caused to lie wholly beyond the ends of the practical 50 printing-line on the platen, so that the plate E will support the paper on the platen without obstructing or obscuring the surface of the paper thereon.

F is a pointer, which is used in connection 55 with the platen to indicate the location thereon of the common printing-point of the series of printing-types, in place of a second or

supplemental letter-space scale mounted on the platen.

It will be understood that in Fig. 1 of the drawings the circle T illustrates the location in the machine of a series of radially-arranged vibratory type-bars, (not shown,) which are adapted to strike or print on the platen at a point common to the series. This 75 feature of type-writing machines is well-known.

The pointer F, the index end of which points to the common printing-point of the type-bar series on the platen, is employed in 80 connection with the platen by being hinged or pivotally mounted on the carriage-frame—as, for example, upon the rod a of said frame—by means of a sleeve f , carrying the pointer, through which sleeve the rod passes loosely. 85 The pointer is curved to conform to the cylindrical surface of the platen and reaches around under the platen to and terminates just below the printing-line thereon, as shown. It is free to swing or vibrate with the platen 90 on the rod a when the platen is lifted to expose the printing-line to the operator, while a novel feature of this pointer is that it is at the same time prevented from longitudinal movement on the rod a with the carriage by 95 means of a lug or pin f' on the bar a' , which engages a peripheral slot f^2 in the sleeve f . The pointer F is preferably thus mounted and arranged on the rod a immediately beneath the pressure-plate E, and extends to the forward edge of said plate on the under face 100 thereof, as shown.

The devices employed to rotate the platen to effect the line-spacing are as follows: G is a lever pivotally mounted on the rod a of the carriage-frame at one end of the platen, and extending forwardly on the carriage across the journal of the platen. This lever is provided with a spring g , fixed on the end yoke a^6 of the carriage-frame, and adapted to press the 105 lever upward to its limit of movement on its said pivot. The lever has on its under side the depending lug g' , which is provided with the segmental guide-slot g^2 , adapted to engage the axis or journal of the platen, as 110 shown. Upon the lever G is pivoted a pawl g^3 , which is adapted in location and direction to engage a ratchet g^4 , fixed on the platen end, and to rotate the platen through the distance of one of the teeth of said ratchet when 115 said lever is vibrated downward against the stress of its spring to the limit of its movement in such direction, and to ride the succeeding tooth of the ratchet and assume a position in line above it when the lever G is 120 retracted upward to its limit of movement by its said spring. The pawl g^3 is formed or provided with a weighted heel g^5 beyond its pivot on the lever, so that when the lever is thrown upward the said heel will, by gravity, swing 125 the pawl to its stated position relatively to the ratchet. A downward pressure, therefore, on the free end of the lever G, which end is, as stated, on the forward side of the

carriage, where it may be conveniently manipulated, will operate to rotate the platen the distance of a predetermined space between the lines of printing.

5 What I claim as my invention, and desire to secure by Letters Patent, is—

1. In a type-writing machine, the combination of a rack a^1 on the paper-carriage, spring-controlled dogs C C' to engage and operate said rack, and the universal lever C² to actuate said dogs with a reciprocatory bar C³, composed of two parts united endwise by a screw-joint c⁷, one of which parts is journaled at c⁸ in the arm c of said universal lever, and the other of which parts engages said dogs, substantially as and for the purpose set forth.

2. In a paper-carriage for type-writing machines, the combination of the rotary cylindrical platen B, with a pressure-plate E extending longitudinally and continuously on the platen and having the plane portion e and curved portion e', said plate being provided with the angular perforated end lugs e², bent from said plate and pivotally engaging the hinge-bar a of the platen, and with the spring-arms e³, projecting from the front edge of said plate at the ends thereof and reaching forwardly of the carriage-frame to and seated upon the front rod a² thereof, substantially as and for the purpose set forth.

3. In a paper-carriage for type writing machines, the combination, with the cylindrical platen B, journaled in the carriage-frame hinged to the rod a, of a correspondingly curved pointer F, reaching to the printing-line on the platen and carried by a sleeve f, mounted loosely on the hinge-rod a, and provided with a peripheral slot f², together with

40 a fixed pin f', adapted to engage said peripheral slot and prevent the movement of said

sleeve longitudinally of said hinge-rod, substantially as and for the purpose set forth.

4. In a paper-carriage for type-writing machines, the combination, with the cylindrical platen B, journaled in the hinged yokes a⁵ a⁶, and a correspondingly-curved pressure-plate E, hinged at its ends by lugs e² to the hinge-rod of the platen, and extending longitudinally and continuously on the platen, and provided at its ends with the spring-arms e³, adapted to reach forwardly of the carriage-frame to and be seated on the front rod thereof, of a curved pointer F, carried by a peripherally-slotted sleeve f, mounted loosely on the hinge-rod of the platen and on the rear or under side of said pressure-plate, and a fixed pin f' to engage said slot, said pointer being adapted to reach below and around said pressure-plate to the front edge thereof on the platen, substantially as and for the purpose set forth.

5. In a paper-carriage for type-writing machines, the combination, with the journaled platen provided at one end with the ratchet g⁴, of the spring-controlled lever G, fulcrumed on the rod a of the carriage-frame and extending to the front of the carriage, and provided with lug g', having the guide-slot g² to engage the axle of the platen, together with the pawl g³, pivoted on said lever and adapted to engage the ratchet on the platen when the lever is vibrated downward, and the weighted heel g⁵ on said pawl, whereby the pawl is swung to position above the ratchet when the lever is vibrated upward, substantially as and for the purpose set forth.

EMERY M. HAMILTON.
